(57) **CLAIM**

The ornamental design for a display screen with transitional graphical user interface for an electro-anatomical mapping application, as shown and described.

DESCRIPTION

FIG. 1 is a front view of a first image in a sequence for a display screen with transitional graphical user interface for an electro-anatomical mapping application showing our new design;

FIG. 2 is a second image thereof; and,
FIG. 3 is a third image thereof.

The appearance of the image transitions sequentially between the images shown in FIGS. 1 through 3. The process or period in which one image transitions to another forms no part of the claimed design. The outermost broken line rectangle illustrates a display screen and forms no part of the claimed design. The remaining broken lines, illustrating portions of the graphical user interface, forms no part of the claimed design. The gray broken lines of the graphical user interface form no part of the claimed design.
